COMBINED SHOE POLISH BOX AND APPLICATOR

William C. Harris, 1400 Cedar Creek, Racine, Wis.

Filed Dec. 28, 1959, Ser. No. 58,827

Term of patent 14 years

(Cl. D58—11)

Fig. 4

Fig. 1

Fig. 2

The top of the applicator portion is open.

I claim:

The ornamental design for a combined shoe polish box and applicator, as shown and described.
